US00D986423S

(12) **United States Design Patent** (10) **Patent No.:** **US D986,423 S**
Kiruki et al. (45) **Date of Patent:** **** May 16, 2023**

(54) **ORTHOPEDIC FRAME**

(71) Applicant: **Ossur Iceland ehf**, Reykjavik (IS)

(72) Inventors: **Patrick Kiruki**, Foothill Ranch, CA (US); **Karim De Waard**, Reykjavik (IS)

(73) Assignee: **OSSUR ICELAND EHF**, Reykjavik (IS)

(**) Term: **15 Years**

(21) Appl. No.: **29/729,456**

(22) Filed: **Mar. 26, 2020**

(51) LOC (14) Cl. **24-01**

(52) U.S. Cl.

USPC **D24/190; D29/121.1**

(58) **Field of Classification Search**

USPC D24/188-192; D29/121.1

See application file for complete search history.

(57) **CLAIM**

The ornamental design for an orthopedic frame, as shown and described.

DESCRIPTION

FIG. 1 is a perspective view of an orthopedic frame.

FIG. 2 is a frontal elevational view of the orthopedic frame of FIG. 1.

FIG. 3 is a rear elevational view of the orthopedic frame of FIG. 1.

FIG. 4 is a first plan view of the orthopedic frame of FIG. 1.

FIG. 5 is a second plan view opposite of the first plan view of the orthopedic frame of FIG. 4.

FIG. 6 is a first side elevational view of the orthopedic frame of FIG. 1; and,

FIG. 7 is a second side elevational view of the orthopedic frame of FIG. 1.

The long dashed broken lines immediately adjacent shaded surfaces depict the claim boundary and form no part of the claim. The short dashed broken lines depict portions of an orthopedic frame and form no part of the claim.

1 Claim, 10 Drawing Sheets
